REINFORCED BOAT

Glen E. Robinson, St. Joseph, Mich.

Application August 13, 1934, Serial No. 739,565

9 Claims. (Cl. 114—83)

This invention relates to boats, and is illustrated as embodied in a boat which is reenforced for unusually hard usage, as for a life-boat or for coast guard use and the like.

5 An object of the invention is to reenforce the boat in such a manner that shocks and impacts against any part of the boat will be transmitted and distributed substantially throughout the boat, without any considerable increase in the weight. 10 In one desirable embodiment a light but strong framework, preferably of tubular members welded or otherwise secured together, is provided (ordinarily below the flooring of the boat) and is secured to the keel and side members and to the 15 transverse ribs of the boat, to distribute the shocks as described.

I prefer to provide also on this framework an engine support, or supports for a pair of engines, of novel form and arrangement, so that the inertia forces from the engine (for example when the boat lands with a substantial impact in the surf) are also distributed substantially throughout the boat.

Various features of novelty relate to the manner of securing the framework to the keel member, to the side members, and to the ribs; to the manner of forming and arranging these parts so reenforced to receive the planking of the boat; to the manner of securing the forward ends of the longitudinal tubular members of the framework so that they reenforce the bow; and to other novel combinations of parts and specific arrangements and constructions which will be apparent from the following description of the illustrative embodiment shown in the accompanying drawings, in which:

Figure 1 is a top plan view of my novel reenforced boat, with the decks and upper parts and the flooring omitted to show the reenforcing framework;

Figure 2 is a longitudinal central section through the boat;

Figure 3 is a partial transverse section therethrough on the line 3—3 of Figure 1;

Figure 4 is a partial section through the framework only, on the line 4—4 of Figure 1;

Figure 5 is a partial longitudinal section on the line 5—5 of Figure 1, showing how the framework is attached to the keel member of the boat;

Figure 6 is a partial section on the line 6—6 of Figure 1, showing in elevation one of a set of brackets forming the engine support;

Figure 7 is an enlargement of a part of Figure 3, showing in elevation one of the plates connecting the framework to the ribs of the boat; and

Figures 8 and 9 are respectively plan and sectional views of the bow portion of a boat having a modified construction, and corresponding to the bow portions of Figures 1 and 2 respectively.

The novel reenforced boat shown in Figures 1 to 7 includes a wooden keel member 10, shown as built up in any usual manner of separate parts 12, 14, and 16 at the bow of the boat. The keel member 10 extends in the usual manner longitudinally along the center line of the boat, and is formed along its lower side edges with rabbets receiving the bottom planking 18 of the boat.

The boat also has longitudinal side frame members or chines 20, rabbeted on the sides facing the keel member 10 to receive the bottom planking 18, and formed with upwardly-facing rabbets receiving the side planking 22. There are also transverse ribs 24 arranged in the usual manner connecting the keel member 10 and the side frame members 20, and extending upwardly to carry the side planking 22. While only two such ribs 24 are shown in Figure 1, it will be understood that as many ribs as are desired are to be provided, according to the usual practice. The planking 18 and 22 is nailed or otherwise secured to the ribs 24.

The present invention has to do with reenforcing a boat of this general type, whether or not it is constructed exactly as just described, and especially to providing a light but strong reinforcement arranged to distribute shocks and impacts substantially throughout the boat.

The illustrated reenforcement comprises a framework of tubular members, preferably welded permanently and rigidly together, and underlying and supporting the flooring (not shown) of the boat. This framework is shown as including a relatively strong and large longitudinal tubular member 26 overlying and paralleling the keel member 10, and two sets of somewhat lighter side longitudinally-extending tubular members 28, 30, 32, and 34 arranged in pairs, with the two sets on opposite sides of the member 26, and with the members of each pair arranged one above the other and connected to form a trussed beam by inclined bracing tubular members 34 and (at least where the engine comes) vertical tubular struts 36.

This makes a total of nine longitudinally-extending tubular members opposite the engines, in the particular arrangement illustrated, but the members need not all extend the full length of the boat; for example the members 34 may stop short forwardly of the engines, with their for-

ward ends welded or otherwise permanently secured to the members 32. The braces 34 and the struts 36 are preferably welded permanently to the longitudinal members.

5 The illustrated boat is intended to have two engines, the position of which is indicated in dotted lines at 48 and 42, but the principles of the invention are equally applicable to a boat having a single engine.

10 The engines, arranged with the crankshaft axis inclined in the usual manner as indicated at 44 in Figure 2, are supported in a novel manner by the tubular framework, preferably on rubber blocks or the like carried by series of brackets 46 welded or otherwise secured to the vertical struts 36. Thus, in case of shock, the inertia forces from the engines are distributed by the described novel supporting framework, substantially throughout the boat.

15 20 The manner of securing the keel member 10, the side frame members 20, and the ribs 24, to the novel tubular framework is best shown in Figures 3, 5, and 7.

25 The longitudinally-extending tubular members are tied together at intervals by means such as upper transverse horizontal tubular members 50 and 52 (which carry the flooring of the boat), and by lower inclined transverse members 54 and 56 paralleling the adjacent rib 24, together with braces or struts 58 and 60 shown as connecting members 26 and 28, and 28 and 34, respectively. These parts are all preferably welded permanently together.

30 35 The keel member 10 may be secured, as by bolts 62, to flanges formed on a pair of sheet steel stampings 64 which embrace between them and are bolted or otherwise secured to the corresponding rib 24, and which are formed with openings through which pass the members 26 and 34, and 40 which embrace members 58 between their upper edges. These stampings 64 are preferably welded permanently to members 26 and 34 and, if desired, to members 58.

45 50 Members 30 and 34 each have mounted, and preferably welded, thereon pairs of plates or sheet steel stampings 66 shown on an enlarged scale in Figure 7. The plates of each pair embrace the adjacent rib 24 between them, and are formed at their lower ends with openings for bolts or other fastenings securing them to the rib.

55 Members 32 may have welded thereto tubular struts 68 each carrying a pair of sheet steel stampings 70 embracing between them and bolted or otherwise secured to the rib 24, and formed with flanges similarly secured to the corresponding side frame member 20.

60 65 For convenience, I have only shown two sets of the above-described transverse members, just fore and aft of the engines. For a small boat this will be sufficient. For larger boats additional sets will be used, preferably arranged as described above.

70 75 The forward ends of the members 30 are shown (Figure 4) as slotted vertically entirely therethrough, and members 28 slotted on their lower sides, to receive sheet steel tie members 72 and 74 arranged with their plane surfaces paralleling the boat axis, and welded at their bottom edges to the member 26; the tie members are also preferably welded to the members 30 and 28. A horizontal sheet steel tie member 76 is shown passing through horizontal slots in members 28 and into members 32 through slots formed on their inner

sides, and is preferably welded to the members 28 and 32.

80 85 The tie members 72, 74, and 76 are shown welded or otherwise secured at their forward edges to a transverse vertical sheet steel stamping 78, which is bolted to a transverse structure 80 so that it forms a rigid structural element of this transverse structure. The structure 80 is near enough the bow of the boat to form a pyramidal truss with the sides of the boat, with the bow of 10 the boat forming the apex of the truss.

15 In the modification of Figures 8 and 9, certain ones of the longitudinal tubular members (shown as members 26, 128, and 132) extend forwardly and are carried upward side by side at the bow 15 of the boat, braced against the member 16.

20 While one illustrative arrangement has been described in detail, it is not my intention to limit the scope of the invention to that particular arrangement, or otherwise than by the terms of 20 the appended claims.

I claim:

1. A reenforced boat having a longitudinally-extending keel member of wood, transverse ribs 25 of wood, a framework built up of tubular members extending both longitudinally and transversely of the boat and rigidly secured together to form a trussed self-sustaining structure, and means for securing said structure to said keel member and to said ribs at opposite sides of the 30 boat in such a manner that impacts against any part of the boat are transmitted by said structure to the entire boat.

2. A reenforced boat having a longitudinally-extending keel member of wood, transverse ribs 35 of wood, a framework built up of tubular members extending both longitudinally and transversely of the boat and rigidly secured together to form a trussed self-sustaining structure, means for securing said structure to said keel member 40 and to said ribs at opposite sides of the boat in such a manner that impacts against any part of the boat are transmitted by said structure to the entire boat, and supports for an engine on said structure, whereby in case of shocks and impacts 45 the inertia forces of said engine are distributed by said structure throughout the boat.

3. A reenforced boat having a longitudinally-extending keel member, a tubular longitudinally-extending reenforcing member overlying and secured at intervals to said keel member, transverse ribs, other longitudinally-extending tubular members arranged on both sides of the boat and secured to said ribs, transversely-extending tubular parts connecting and bracing said longitudinally-extending tubular members, said members and parts forming a connected shock-transmitting framework which is structurally independent of the keel member and ribs, and engine-supporting means carried by certain of said longitudinally-extending tubular members.

4. A reenforced boat having a longitudinally-extending keel member, a tubular longitudinally-extending reenforcing member overlying and secured at intervals to said keel member, transverse ribs, other longitudinally-extending tubular members arranged on both sides of the boat and secured to said ribs, and transversely-extending tubular parts connecting and bracing said longitudinally-extending tubular members, 70 said members and parts forming a connected shock-transmitting framework which is structurally independent of the keel member and ribs.

5. A reenforced boat having a longitudinally-extending keel member having rabbets formed 75

- along its lower side edges, a longitudinally-extending tubular reenforcing member overlying and secured to said keel member, transverse ribs, side longitudinal frame members formed with 5 rabbets facing the rabbets of the keel member and with upwardly-facing rabbets, a reenforcing framework of tubular metal parts secured to said longitudinally-extending member and to said side frame members and to at least some of said 10 ribs, a bottom planking secured to the bottoms of said ribs and seated in the rabbets of the keel member and the corresponding rabbets of the side members, and side planking secured to said ribs and seated in the upwardly-facing rabbets of 15 the side frame members, whereby shocks against the bottom of the boat are distributed substantially throughout the boat by said framework.
6. A reenforced boat having a longitudinally-extending keel member having rabbets formed 20 along its lower side edges, a longitudinally-extending tubular reenforcing member overlying and secured to said keel member, transverse ribs, side longitudinal frame members formed with rabbets facing the rabbets of the keel member, a 25 reenforcing framework of tubular metal parts secured to said longitudinally-extending member and to said side frame members and to at least some of said ribs, and a bottom planking secured to the bottoms of said ribs and seated in the rabbets of the keel member and the corresponding rabbets of the side members, whereby shocks against the bottom of the boat are distributed substantially throughout the boat by said framework. 30
7. A reenforced boat having a longitudinally-extending keel member having rabbets formed along its lower side edges, a longitudinally-extending tubular reenforcing member overlying and secured to said keel member, transverse ribs, 35 side longitudinal frame members formed with rabbets facing the rabbets of the keel member, a reenforcing framework of tubular metal parts secured to said longitudinally-extending member and to said side frame members and to at least some of said ribs, and a bottom planking secured to the bottoms of said ribs and seated in the rabbets of the keel member and the corresponding rabbets of the side members, whereby shocks against the bottom of the boat are distributed substantially throughout the boat by said framework. 40
8. A reenforced boat having a reenforcing framework including longitudinally-extending tubular members which converge toward the bow of the boat, tie members secured to said tubular members and tying them together adjacent the bow of the boat and which are arranged with plane portions paralleling the boat axis and seated in slots in said tubular members, and a member perpendicular to the boat axis and secured to the front edges of said tie members and forming part of a transverse structural part of the boat. 15
9. A reenforced boat comprising a keel member and two side frame members at opposite sides of the boat and having a rib connecting the keel member and the side frame members and which extends upwardly from the side frame members to form parts of the sides of the boat, a reenforcing framework connecting said side frame members and keel member independently of the rib, and means for securing said framework to the keel member and the side frame members including pairs of plates secured to the framework and to said side frame members and embracing and secured to said rib. 20
10. A reenforced boat having a longitudinally-extending keel member having rabbets formed along its lower side edges, a longitudinally-extending tubular reenforcing member overlying and secured to said keel member, transverse ribs, side longitudinal frame members formed with rabbets facing the rabbets of the keel member, a reenforcing framework of tubular metal parts secured to said longitudinally-extending member and to said side frame members and to at least some of said ribs, and a bottom planking secured to the bottoms of said ribs and seated in the rabbets of the keel member and the corresponding rabbets of the side members, whereby shocks against the bottom of the boat are distributed substantially throughout the boat by said framework. 25
11. A reenforced boat comprising a keel member and two side frame members at opposite sides of the boat and having a rib connecting the keel member and the side frame members and which extends upwardly from the side frame members to form parts of the sides of the boat, a reenforcing framework connecting said side frame members and keel member independently of the rib, and means for securing said framework to the keel member and the side frame members including pairs of plates secured to the framework and to said side frame members and embracing and secured to said rib. 30
12. A reenforced boat having a longitudinally-extending keel member having rabbets formed along its lower side edges, a longitudinally-extending tubular reenforcing member overlying and secured to said keel member, transverse ribs, side longitudinal frame members formed with rabbets facing the rabbets of the keel member, a reenforcing framework of tubular metal parts secured to said longitudinally-extending member and to said side frame members and to at least some of said ribs, and a bottom planking secured to the bottoms of said ribs and seated in the rabbets of the keel member and the corresponding rabbets of the side members, whereby shocks against the bottom of the boat are distributed substantially throughout the boat by said framework. 35
13. A reenforced boat having a longitudinally-extending keel member having rabbets formed along its lower side edges, a longitudinally-extending tubular reenforcing member overlying and secured to said keel member, transverse ribs, side longitudinal frame members formed with rabbets facing the rabbets of the keel member, a reenforcing framework of tubular metal parts secured to said longitudinally-extending member and to said side frame members and to at least some of said ribs, and a bottom planking secured to the bottoms of said ribs and seated in the rabbets of the keel member and the corresponding rabbets of the side members, whereby shocks against the bottom of the boat are distributed substantially throughout the boat by said framework. 40

GLEN E. ROBINSON. 40
